(57) **CLAIM**

The ornamental design for an external lens for mobile phone, as shown and described.

DESCRIPTION

FIG. 1 is a perspective view of an external lens for mobile phone showing my new design in a used condition;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top view thereof;

FIG. 8 is a bottom view thereof;

FIG. 9 is a perspective view thereof, with the top portion removed and the bottom portion shown separately for ease of illustration;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top view thereof;

FIG. 15 is a bottom view thereof;

FIG. 16 is a perspective view thereof, with the bottom portion removed and the top portion shown separately for ease of illustration;

FIG. 17 is another perspective view thereof;

FIG. 18 is a front elevation view thereof;

FIG. 19 is a rear elevation view thereof;

(Continued)

FIG. 20 is a left side elevation view thereof;
 FIG. 21 is a right side elevation view thereof;
 FIG. 22 is a top view thereof; and,
 FIG. 23 is a bottom view thereof.
 The broken (dashed) lines show portions of the external lens
 for mobile phone that form no part of the claimed design.
